UNITED STATES PATENT OFFICE.

DAVID GESTETNER, OF LONDON, ENGLAND, ASSIGNOR TO D. GESTETNER, LIMITED, OF LONDON, ENGLAND.

DUPLICATING.

Application filed December 8, 1921, Serial No. 521,240, and in Great Britain December 15, 1920.

This invention relates to the method of duplicating involving the use of stencils, comprising a stencil layer produced by photographic means on a porous support as, for instance, Yoshino paper.

Such stencils are ordinarily produced by exposing to the action of light, a sheet of sensitized gelatine on a suitable support behind the matter to be reproduced or a negative or diapositive produced therefrom and then after development transferring the image to a sheet of Yoshino paper.

The object of the present invention is to provide improvements in the production of such stencils.

According to the invention the stencil layer is produced by causing a silver image formed by the action of light upon a light sensitive silver salt to interact chemically with a composition, as for instance, bichromated gelatine, in order to change the solubility of the composition in a medium used as a developer.

The invention in one phase comprises producing a print by the action of light upon a silver compound such, for instance, as is employed in coating "bromide" paper, and bringing together the print and a pellicle of a composition adapted by the chemical action of the silver image on the colloid to change in respect of its solubility in a developing medium, under conditions to effect such change, and developing the pellicle of composition.

The silver image may be treated, if necessary, in order to cause it to effect the desired changes in the composition, or the composition may contain or be treated with an agent adapted to be acted upon by the silver image, in order that the solubility of the composition may be affected in the desired manner.

The pellicle of composition may be coated on a temporary support from which it will be transferred to a final support of a porous character, as for instance Yoshino paper, or it may in the first instance be coated on such final support, in which case it may be desirable to bring the back of the coated support into contact with the silver print.

Alternatively, the material adapted to act as the final support may be coated or treated with a composition containing a suitable light sensitive silver compound and after producing thereon a silver print, a pellicle of a suitable composition, as for instance, bichromated gelatine, may be applied thereto, in conditions adapted to effect the desired change in the solubility of the composition.

The silver print in either case may be treated, if the pellicle or layer is a gelatine composition, in order to bleach or reverse the image, with a medium of known character such as a solution of potassium bichromate, potassium ferricyanide, and potassium bromide.

Another phase of the invention comprises producing by photographic means a silver image in a layer of an emulsion of a light sensitive silver salt in unhardened gelatine or a like material the solubility of which in a medium used subsequently as a developer (hot water in the case of gelatine) is adapted to be changed in accordance with the intensity of light action on the said layer, treating the said layer to effect the desired change in solubility and developing the treated layer, in order to dissolve or wash out the portions of the gelatine or the like which have not been insolubilized.

The layer of emulsion may be constituted by a gelatine emulsion resembling the emulsion used in making bromide paper, but which however, is not hardened, and the support coated with this emulsion may be exposed, treated in the usual way to produce a silver print, after which it is treated if necessary with an agent adapted, with or without further exposure to light, to change the solubility of the gelatine in the medium subsequently used as a developer at the light affected or light unaffected portions and finally developed.

Alternatively, a support similarly coated, after exposure and development of the silver image may be sensitized by means of a suitable agent as, for instance, a bichromate exposed to the action of light, if necessary or desirable, and redeveloped to remove

those portions of the gelatine layer which have been less affected by the action of light as the result of the silver image preventing or reducing the action of light upon the sensitizing agent.

The gelatine emulsion in this phase of the invention may be supported on a porous material, as for instance, Yoshino paper, adapted to act as the final support.

10 Alternatively, the gelatine emulsion may be coated on a support from which it may be stripped and transferred to a suitable final support for use as a stencil.

The invention also comprises exposing 15 the support provided with a light sensitive silver compound in a camera in order to produce thereon an image of the matter to be reproduced and using the image thus produced in one or other of the manners 20 indicated above in producing a stencil and thereby avoiding the necessity of producing first a negative and then a diapositive from the negative and finally a print from the diapositive adapted for use as a stencil.

25 In order that the invention may be better understood, reference may be had to the accompanying drawings, in which:—

Figures 1 and 2 are respectively a section 30 and elevation of a print produced by the action of light on a silver compound;

Figure 3 shows in section a print as shown in Figures 1 and 2 in contact with a sheet of paper coated with bichromated gelatine;

35 Figure 4 is a view showing the sheet of paper coated with gelatine after it has been developed while

Figure 5 is a section of a sheet as shown in Figure 4 with developed gelatine layer in contact with a sheet of Yoshino paper.

40 Figure 6 is a view in section of the stencil;

Figure 7 is a view in section of a sheet of Yoshino paper coated with bichromated gelatine and in contact with a silver negative print of the matter to be reproduced;

45 Figures 8 and 9 are views in section of a sheet of Yoshino paper treated with a light sensitive silver compound respectively before and after exposure to the action of light;

50 Figure 10 shows a print as in Figure 7 in contact with a sheet of paper coated with bichromated gelatine in order that the reduced silver may insolubilize portions of the bichromated gelatine;

55 Figure 11 is a plan view showing the completed stencil;

Figure 12 is a view in section of a sheet 60 of paper coated with a bichromated gelatine emulsion containing a light sensitive silver salt with a layer of wax between the emulsion and the paper support;

Figure 13 is a view in section of the same 65 after exposure to the action of light and development of the silver image in contact with the sheet of Yoshino paper, the paper

backing forming the original support for the bichromated gelatine being shown in the process of removal,

Figure 14 being a similar view of the sheet of Yoshino paper after it has been treated in order to remove the portions of the coating transferred to it which have been rendered insoluble in the developer;

Figure 15 illustrates a sheet of Yoshino paper coated with a bichromated gelatine 75 emulsion containing a light sensitive silver salt, while

Figure 16 is a view in section of the same after it has been exposed to the action of light, developed in order to reduce the light affected silver salt and treated with hot water in order to remove the still soluble gelatine, and

Figure 17 is a view in elevation of the 80 same.

Referring to Figures 1 to 5, 1 indicates a paper support, 2 portions of the light sensitive coating thereon which have been affected by light, 3 the portions which have been 85 unaffected by light. 4, in Figure 3, illustrates a sheet of paper provided with a coating of bichromated gelatine, the portions 5 of which have been rendered insoluble, whereas the portions 6 have remained soluble 90 in consequence of their being unacted upon by the reduced silver, the said sheet having its gelatine coating in contact with a silver print, as shown in Figures 1 and 2.

Figure 4 illustrates in elevation the sheet 100 of paper 7 coated with bichromated gelatine after it has been stripped from the silver print and developed with hot water, the reference 8 indicating the portion from which the gelatine which has not been rendered insoluble has been removed.

In Figure 5, 9 indicates a sheet of Yoshino paper and 10 a coating of gelatine thereon, the sheet of paper 7 acting as a support for the same during development, being also in 110 contact with the gelatine.

Figure 6 is a section of the finished stencil, in which like parts are indicated by like references, after the sheet of paper acting as temporary support for the gelatine has 115 been stripped off.

Referring to Figure 7, 11 is a sheet of Yoshino paper, 12 a coating of bichromated gelatine thereon, 13 the light affected portions of a light sensitive positive, 14 the portions thereof which have not been affected by light, and 15 the support for the said composition.

120 In Figure 8, 16 indicates a sheet of Yoshino paper, 17 a coating of a light sensitive silver compound thereon, while in Figure 9, 18 indicates the portions of the silver compound which have been affected by light and 19 the portions which have not been so affected.

Similar references are used in Figure 10 to denote like parts, the print as shown in section in Figure 9 being in this figure illustrated in contact with a coating of bichromated gelatine 20 on a support 21 formed of paper or the like. This support is stripped from the bichromated gelatine after treatment to cause the silver image to interact with the bichromated gelatine whereby portions of the same will have been rendered insoluble. After stripping the support from the bichromated gelatine and treating the latter in order to remove the still soluble portions a stencil, as shown in Figure 11, is obtained, the reference 22 in this figure indicating the Yoshino paper while 23 represents the insolubilized bichromated gelatine. In Figure 12, 24 indicates a temporary support of sheet material, 25 a coating of wax or the like thereon and 26 a coating of bichromated gelatine emulsion containing a light sensitive silver salt. By exposure of the coated support certain areas of the light sensitive coating will be affected by light and will be reduced on development, the reduced silver reacting with the bichromate present in the gelatine emulsion, converting the same into chromium salts which render the portions of the gelatine, where such action has taken place, insoluble.

In Figure 13, 27 indicates a sheet of Yoshino paper which has been brought into contact and caused to adhere to the bichromated gelatine. This figure shows the original support for the bichromated gelatine in process of removal.

In Figure 14, 28 indicates the Yoshino paper, 29 the insolubilized gelatine in contact therewith, and 30 the openings in the stencil through which ink will be caused to pass when the stencil is in use.

In Figure 15, 31 indicates the sheet of Yoshino paper, 32 a layer of a bichromated gelatine emulsion of a light sensitive silver salt supported thereon, while in Figure 16, 33 indicates a sheet of Yoshino paper, 34 the portions of the bichromated gelatine emulsion which have been rendered insoluble by exposure to light and 35 the apertures or openings therein through which the ink will be caused to pass in the operation of duplicating.

Figure 17 is a view in elevation of the stencil, like parts being indicated by like references.

Having now described my invention what I claim as new and desire to secure by Letters Patent is:—

1. The process of producing stencils on a Yoshino paper base, which comprises producing a print by the action of light upon a silver bromide emulsion coated on a support, bringing together the print on said support and a pellicle of composition

adapted by the chemical action of the silver image on the composition of which the pellicle is formed to change the same in respect to its solubility in a developing medium, under conditions to effect such change, developing the pellicle of composition and transferring the developed pellicle to a sheet of Yoshino paper. 70

2. The process of producing stencils on a Yoshino paper base, which comprises producing a print by the action of light upon a silver bromide emulsion coated on a support and bringing together the print on said support and a pellicle of bichromated gelatine under conditions adapted to cause the silver image to form salts of chromium as a base in the bichromated gelatine, whereby portions of the gelatine will be rendered insoluble, developing the pellicle thus treated with hot water and transferring the developed pellicle to a sheet of Yoshino paper. 80

3. The process of producing stencils on a Yoshino paper base, which comprises causing an image formed by the action of light on a light sensitive silver salt to effect a chemical change in bichromated gelatine, whereby areas of the bichromated gelatine will be rendered insoluble in hot water and subjecting the bichromated gelatine after such treatment to the action of hot water to remove the still soluble portions, thereby obtaining an insoluble gelatine image adapted for use as a stencil. 90

4. The process of producing stencils on a Yoshino paper base, which comprises causing an image formed by the action of light on a light sensitive silver salt to effect a chemical change in bichromated gelatine, whereby areas of the bichromated gelatine will be rendered insoluble in hot water and subjecting the bichromated gelatine after such treatment to the action of hot water to remove the still soluble portions, and transferring the insoluble gelatine image 100 thus obtained to a sheet of Yoshino paper. 105

5. The process of producing stencils on a Yoshino paper base, which comprises exposing a support provided with a coating including a light sensitive silver compound to projected light in order to produce therein a latent image of the matter to be reproduced, developing said image, bringing together said developed image and a pellicle of a composition adapted by the chemical action of the silver image on the composition of which the pellicle is formed to change the same in respect to its solubility in a developing medium, under conditions to effect such change, developing the pellicle of composition and transferring the developed pellicle to a sheet of Yoshino paper. 115

6. The process of producing stencils on a Yoshino paper base, which comprises ex- 120

posing a support provided with a coating including a light sensitive silver compound to projected light in order to produce there-in a latent image of the matter to be re-produced, developing said image, bringing together said developed image and a pellicle of bichromated gelatine under conditions adapted to cause the silver image to form salts of chromium as a base in the

bichromated gelatine, whereby portions of 10 the gelatine will be rendered insoluble, developing the pellicle thus treated with hot water and transferring the developed pellicle to a sheet of Yoshino paper.

In testimony whereof I have signed my 15 name to this specification.

DAVID GESTETNER.
